The ornamental design for a mini stepper with flat steps, as shown and described.

DESCRIPTION

FIG. 1 is a top front perspective view of a mini stepper with flat steps, showing my new design;

FIG. 2 is a top plan view thereof;

FIG. 3 is a bottom view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a lower front perspective view.

The broken lines shown in the figures are for the purpose of illustrating portions of the mini stepper with flat steps, which form no part of the claimed design.
